UNITED STATES PATENT OFFICE.

WALTER R. COLEY, OF PHILADELPHIA, PENNSYLVANIA, ASSIGNOR TO LEEDS & NORTHRUP COMPANY, OF PHILADELPHIA, PENNSYLVANIA, A CORPORATION OF PENNSYLVANIA.

GALVANOMETER.

Application filed March 20, 1924. Serial No. 700,577.

My invention relates to galvanometers, and more particularly of the type having a moving system comprising a coil deflecting or rotatable in a magnetic field.

In accordance with my invention, the sensitivity of a galvanometer is increased many fold, as of the order of five to ten fold, by utilizing magnetic impurity of the moving system, as, for example, a slight amount of magnetic foreign material, such as iron or the like, adhering to or within the movable coil and disposed in the magnetic field in which the coil moves, to produce a torque opposing the torque of the suspension or mounting of the coil to produce an effect equivalent to the use of a more delicate suspension or mounting for the coil which is finer or weaker than the suspension or mounting actually employed, and thereby effecting a material increase in the sensitivity and the period of vibration of the moving coil system.

My invention resides in a method of and means for increasing the sensitivity of a galvanometer as hereinafter described and claimed.

For an understanding of my method and for an illustration of one of the various forms my structure may take, reference is to be had to the accompanying drawing in which;

Fig. 1 is a front elevational view of a galvanometer structure embodying my invention.

Fig. 2 is a side elevational view, partly in vertical section, of the structure shown in Fig. 1.

Fig. 3 is a rear elevational view of the structure shown in Fig. 1.

Fig. 4 is a horizontal sectional view taken on the line 4—4 of Fig. 3.

Fig. 5 is a fragmentary perspective view of a part of my structure.

It has heretofore been known that in a movable coil structure of a sensitive galvanometer there has generally been unintentionally present magnetic impurity in the form of minute particle or particles of magnetic foreign material, such as iron or other magnetizable material, which is invisible, or partially so, to the unaided eye, or which may be within the wire or conductor of the coil itself, in its enamel or other insulation, or otherwise in or adherent to the coil. It has been proposed to render magnetic im-

purity innocuous or of no effect by so modifying the magnetic field, as by rendering it radial, that the torque produced by the action of the magnetic field upon the magnetic impurity is reduced to zero, in which case the natural period of the moving coil system is the same both when disposed in the magnetic field and when removed therefrom.

In accordance with my invention however, advantage is taken of the presence of magnetic impurity adhering to or in the coil and disposed in the magnetic field in which the coil is movable, or so called magnetic impurity is added to that already present in the movable coil system, or in the rare cases when no magnetic impurity is present, sufficient is added, and the magnetic field is so modified, adjusted, distorted or controlled that it produces a torque, by its action upon the magnetic impurity, which is caused to oppose the torque exerted upon the moving coil by its filar or other suspension or mounting so that the net torque exerted upon the moving coil system and opposing the torque caused by the current flowing through the coil while in the magnetic field is materially reduced with the result that the natural period of the moving coil system while in the magnetic field is greatly prolonged or increased, even to the extent of attaining a period three or four times the period of the coil system when removed from the magnetic field, and the sensitivity of the galvanometer is consequently increased to even a greater extent than the increase in the natural period.

In accordance with my invention the sensitivity of the galvanometer is increased many fold, as of the order of five to ten fold that of the highest sensitivity heretofore obtained so far as I am aware. For example, it is not uncommon by the practice of my invention to attain a current sensitivity of the order of 10^{-11} (ten to the minus eleventh power) ampere.

While it is theoretically possible to attain extremely high sensitivity by employing a filar or other suspension of suitably small cross section and effecting suitably small torque, in practice this is impossible and the filar or other suspension must be sufficiently rugged to withstand handling and shipping, and this necessarily involves a suspension of greater cross section and effecting greater torque notwithstanding such greater cross

- section and greater torque of a sufficiently rugged suspension, in accordance with my invention I am enabled to procure extremely high sensitivity by causing the magnetic impurity, present or applied, to exert a torque of suitable magnitude opposing that of the sufficiently rugged suspension, with the result equivalent to that obtainable by a far smaller or more delicate suspension.
- 10 Referring to the drawing, M is a permanent magnet carried by any suitable support or base, not shown, and exhibiting at its ends, as usual, north and south poles N and S. Carried by the same support or base, or by any other suitable means, is the fixed vertically extending metallic non-magnetic member or plate A carrying at its upper end an adjustable torsion head a to which is attached the upper end of the filar suspension, such as a wire or, as indicated, ribbon b secured at its lower end to the member e, secured to the rotatable coil C in its axis of rotation. Carried by the member e, or otherwise suitably attached to the coil or its suspension is the usual mirror d, which reflects a spot of light upon a stationary galvanometer scale, which is generally straight, but which may take any other suitable form, as well understood in the galvanometer art. Attached to the coil C at its lower end in its axis of rotation is the lower filar suspension member e attached at its lower end to the post or stud f carried by but insulated from the member A as well understood in the art. Current enters by one of the filar suspension members, as b, flows through the turns or convolutions of the coil C, and passes out by the other filar suspension member e.
- 40 The cylindrical core member g, of magnetizable material, such as soft iron, is secured by screws h, h to the member A, the screws extending through the block i of non-magnetic material, the member A, and the spacing member or members j of non-magnetic material, and threading into the core g. Engaging or disposed closely adjacent the poles N and S of the permanent magnet M are the rear faces k of the pole pieces m, m, of soft iron or equivalent magnetizable material detached from magnet M and having the cylindrical or other suitably formed pole faces n, n between which and the core g is formed an annular or equivalent air gap within which is rotatable the coil C whose axis of rotation is the filar suspension b, e.
- 60 Extending through the slots o in the rectangular portion p of the plate A are the screws q, two for and threading into each of the pole pieces m, thereby holding and supporting the pole pieces m to and upon the member A, to permit their adjustment laterally, as viewed in Figs. 1 and 4, with respect to the coil C, while maintaining co-

operative relation with the poles N and S of the magnet M. Each of the pole pieces m is provided with one or more threaded holes r in which is threaded an adjusting screw s, of fine pitch, abutting against the side faces t of the portion p of the plate A, whereby rotatable adjustment of the screws s will with great nicety determine the lateral adjustment of the pole piece m toward or away from the coil C, the pole piece being detached from but remaining in operative relation with the pole of the magnet M. By so adjusting either or both of the pole pieces m, the magnetic field between the pole pieces m, m and in which the coil C with its magnetic impurity is located, the magnetic field is so modified, distorted, directed or controlled that the torque caused by the action of the magnetic field upon the magnetic impurity is caused to have such magnitude and to act in such sense or direction as to oppose the torque caused by or due to the filar suspension b, e, or its equivalent, with the result that the net torque exerted upon or by the coil C in opposition to the torque caused by reaction between the magnetic field and the current traversing the conductor of which the coil C is wound, is greatly reduced, yielding markedly increased sensitivity which could otherwise be attained only by use of much finer or much more delicate suspension. The effect of the torque due to magnetic impurity is, as aforesaid, greatly to increase the natural period of oscillation or vibration of the coil C or the oscillatory system of which it is a part, and its natural period may be increased to three or four fold the natural period which the coil system has when removed from the magnetic field, with the result that the sensitivity is greatly increased, and so securing a sensitivity five to ten times the maximum sensitivity heretofore obtainable, so far as I am aware, with structure the same as regards shape, size and number of turns of coil, and as regards the suspension and the torque exerted thereby.

In the example illustrated, the magnetic field as effected by the cylindrical core g, and the pole faces n, is normally radial or uniform. Upon adjustment of either or both of the pole pieces m from the position effecting such uniform or radial field, the magnetic impurity of, or the slight amount of magnetic material applied to the coil C, located practically anywhere thereon, as at either end or, and preferably, at either vertical side, is acted upon by a modified or non-uniform field effecting a torque upon the coil. The direction of adjustment of a pole piece is that which causes the torque exerted by the magnetic material of or on the coil to oppose the torque exerted upon the coil by its suspension, with resultant in-

crease in sensitivity and natural period of the galvanometer. The extent of the adjustment of a pole piece in the aforesaid direction is preferably such that the algebraic sum of the torques exerted by the suspension and magnetic material is small and tends toward zero. 70

While the torque exerted by the coil suspension bears a linear relation to the angular displacement of the coil from zero or normal position, the opposing torque effected by the magnetic impurities varies in accordance with a trigonometric function, as the cosine, of the angle between the direction of the magnetic field and the direction of motion of the coil. In consequence there is a tendency to disturb the linear relation between strength of current traversing the coil C and the angular displacement of the coil. 75

This however is not serious for small angular displacement of the coil, and is partly corrected because the beam of light reflected from the mirror d on to a straight scale is affected by a tangent law. However, when the galvanometer is used in so called null methods, or under circumstances where the angular deflections of the coil system from zero are small, the aforesaid variation from linear relation is inconsequential. 80

30. What I claim is:

1. The method of decreasing the torque exerted by its suspension upon a galvanometer coil deflecting in a magnetic field which comprises modifying the magnetic field in which the coil moves to effect upon the coil in opposition to the torque of the suspension a torque due to the action of said magnetic field upon magnetic material disposed in said field and controlled by said suspension. 100

2. The method of increasing the sensitivity of a galvanometer comprising a coil deflecting, when traversed by current, in a magnetic field in opposition to a coil-controlling torque which comprises modifying said magnetic field to produce a torque opposing said coil-controlling torque by the action of said magnetic field upon magnetic material disposed in said field and movable therein with said coil. 110

3. The method of increasing the sensitivity of a galvanometer comprising a coil deflecting, when traversed by current, in a magnetic field in opposition to a coil-controlling torque which comprises modifying said magnetic field to produce a torque opposing said coil-controlling torque by the action of said field upon magnetic impurity of said coil. 115

60. 4. The combination with a galvanometer comprising a coil deflecting in a magnetic field when traversed by current, and means producing a torque opposing deflection of said coil, of magnetic material disposed in said field and movable with said coil, and

means for modifying said magnetic field to produce by the action of said field upon said magnetic material a torque of such magnitude and effective in such direction as materially to increase the sensitivity of the gal- 70

5. The combination with a galvanometer comprising a coil deflecting in a magnetic field when traversed by current, and means producing a torque opposing deflection of 75 said coil, of magnetic material disposed in said field and movable with said coil, and means for modifying said magnetic field to produce by the action of said field upon said magnetic material a torque opposing the 80 torque produced by said means.

6. The combination with a galvanometer comprising a coil having magnetic impurity and deflecting in a magnetic field when traversed by current, and means producing a 85 torque opposing deflection of said coil, of adjustable means for modifying said field to effect by the action thereof upon said impurity a torque affecting deflection of said coil. 90

7. The combination with a galvanometer comprising a coil having magnetic impurity and deflecting in a magnetic field when traversed by current, and means producing a 95 torque opposing deflection of said coil, of adjustable means for modifying said field to effect by the action thereof upon said impurity a torque opposing the torque produced by said means.

8. The combination with a galvanometer comprising a coil having magnetic impurity and deflecting in a magnetic field when traversed by current, and means producing a 100 torque opposing deflection of said coil, of means for imparting a sensitivity greater than that due to said torque producing means comprising adjustable means for modifying said magnetic field to effect by its action upon said impurity a torque of such magnitude and acting in such direction as to increase the period of said coil to a magnitude greater than the period due to said torque producing means. 110

9. In combination with a galvanometer comprising a coil, a magnet having pole piece structure for producing a field in which said coil deflects when traversed by current, and means producing torque opposing deflection of said coil, of magnetic material disposed in said field and movable therein with said coil, and means for effecting adjustment of said pole piece structure with respect to said magnetic material for effecting a coil-controlling torque due to the action of said field upon said magnetic material. 115

10. In combination with a galvanometer comprising a coil, a magnet having pole piece structure for producing a field in which said coil deflects when traversed by 120

- current, and means producing torque opposing deflection of said coil, of magnetic material disposed in said field and movable therein with said coil, and means for effecting 5 adjustment of said pole piece structure with respect to said magnetic material to effect by the action of said field upon said magnetic material a torque opposing the torque produced by said means.
- 10 11. The combination with a galvanometer comprising a coil having magnetic impurity, a magnet having pole piece structure for producing a magnetic field in which said coil deflects when traversed by current, and 15 a coil suspension opposing its deflection, of means for effecting adjustment of said pole piece structure for procuring by the action of said field upon said impurity a coil-controlling torque.
- 20 12. The combination with a galvanometer comprising a coil having magnetic impurity, a magnet having pole piece structure for producing a magnetic field in which said coil deflects when traversed by current, and 25 a coil suspension opposing its deflection, of means for effecting adjustment of said pole piece structure for procuring by the action of said field upon said impurity a torque opposing the torque exerted by said suspension.
- 30 13. The combination with a galvanometer comprising a permanent magnet, pole pieces therefor detached therefrom, a coil deflecting when traversed by current in the magnetic field between said pole pieces, means 35 producing torque opposing deflection of said coil, and means for varying the sensitivity comprising magnetic material disposed in said field and movable with respect to said 40 magnet and said pole pieces for producing by the action of said field as modified by said pole pieces upon said magnetic material a torque acting upon said coil.
- 45 14. The combination with a galvanometer comprising a permanent magnet, pole pieces therefor detached therefrom, a coil deflecting when traversed by current in the magnetic field between said pole pieces, means 50 producing torque opposing deflection of said coil, and means for varying the sensitivity comprising magnetic material disposed in said field and movable with said coil, and means for adjusting a pole piece with respect to said magnet and said magnetic material 55 for producing by the action of said field upon said magnetic material a torque opposing the torque produced by said means.
- 60 15. The combination with a galvanometer comprising a permanent magnet, pole pieces therefor detached therefrom, a coil having 65 magnetic impurity and deflecting in the field between said pole pieces when traversed by current, and means producing torque opposing deflection of said coil, of means for increasing the sensitivity comprising means for adjusting said pole pieces to distort said magnetic field to effect by its action upon said magnetic impurity a torque opposing the torque produced by said means.
- 70 16. A galvanometer comprising a magnet, pole pieces therefor, a core disposed in the magnetic field between said pole pieces, a coil and magnetic material movable therewith in the field between said pole pieces and core, a member supporting said pole pieces in detached relation to said magnet, a coil suspension carried by said member, and means for adjusting at least one of said pole pieces with respect to said member.
- 75 17. A galvanometer comprising a magnet, pole pieces therefor, a core disposed in the magnetic field between said pole pieces, a coil having magnetic impurity and movable in the field between said pole pieces and core, a member supporting said pole pieces in detached relation to said magnet, a coil suspension carried by said member, and means for adjusting at least one of said pole pieces with respect to said member.
- 80 18. A galvanometer comprising a magnet, pole pieces therefor, a supporting member, a core carried by said supporting member and disposed between said pole pieces, a coil movable in the field between said pole pieces and core, a suspension for said coil carried by said supporting member, said coil having magnetic impurity, said pole pieces carried by said supporting member in detached relation to said magnet, and means for adjusting each of said pole pieces with respect to said supporting member for distorting said field to effect by the action of said field upon said impurity a torque in opposition to said suspension.
- 85 19. A galvanometer comprising a permanent magnet having plane pole faces, pole pieces, each having faces coacting respectively with said face of said supporting member and with one of said pole faces of said magnet, a core disposed between said 90 pole pieces and supported by said supporting member, a coil having magnetic impurity disposed in the field between said pole pieces and said core, a suspension for said coil carried by said supporting member, and a screw threaded in each of said pole pieces and adapted to engage said supporting member for effecting adjustment of the pole piece to distort the magnetic field to produce by its action upon said magnetic impurity a 95 torque opposing the torque produced by said suspension.
